UNITED STATES PATENT OFFICE

146,498

DESIGN FOR A FONT OF TYPE OR SIMILAR ARTICLE

George E. Dietze, Pittsburgh, Pa., assignor of one-half to Harry J. Wald and Leon Wald, both of Pittsburgh, Pa.

Application April 13, 1946, Serial No. 128,566

Term of patent 14 years

(Cl. D64—12)

To all whom it may concern:

Be it known that I, George E. Dietze, a citizen of the United States of America, residing at Pittsburgh, in the county of Allegheny and State of Pennsylvania, have invented a new, original, and ornamental Design for a Font of Type or Similar Article, of which the following is a specification, reference being had to the accompanying drawing, forming part thereof.

The drawing illustrates face views of a font of type, showing my new design.

I claim:

The ornamental design for a font of type or similar article, as shown.

GEORGE E. DIETZE.
